Primary Examiner — George A Bugg*Assistant Examiner* — Jessica A Junkins(74) Attorney, Agent, or Firm — Fross, Zelnick, Lehrman & Zissu, PC; Charles T.J. Weigell, Esq.(57) CLAIM

The ornamental design for a waist pack as shown and described.

DESCRIPTION

FIG. 1 is a perspective view of a waist pack showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the figures represent portions of the waist pack that form no part of the claimed design.
